UNITED STATES PATENT OFFICE

2,662,441.

METHOD OF MAKING EXPLOSIVE ASSEMBLIES

William R. Farren, Kennett Square, Pa., assignor to Atlas Powder Company, Wilmington, Del., a corporation of Delaware.

Application June 23, 1948; Serial No. 34,617

1 Claim. (Cl. 86—20)

1. The present invention relates to explosive assemblies.

An object of the invention is the provision of an explosive assembly which is easy to use.

Another object of the invention is the provision of an explosive assembly which does not require the concurrent use of a primer element.

A further object of the invention is the provision of an explosive assembly containing a primer element and a base explosive in one convenient package.

A still further object of the invention is the provision of an explosive assembly which may be easily provided with a separate primer or core element.

Still another object of the invention is the provision of an improved method of manufacturing an explosive assembly.

Other objects will be apparent from the following description.

One common explosive assembly designed for use in large diameter bore holes includes a shell made from a tube gathered together with a wire tie at one end and capped or crimped at the other end. Explosive assemblies of this type often contain a relatively sensitive core explosive surrounded by a less sensitive or lower velocity main, or base charge, explosive. Often the base charge explosive has been so insensitive, particularly when wet, as not to be subject to reliable initiation by means of ordinary commercial blasting caps. Because of this insensitivity, it has been customary to initiate explosive assemblies of the type just described by means of separate primer cartridges of more sensitive explosive which can be initiated by blasting caps.

Ordinary nitroglycerin dynamite, and particularly gelatin dynamite, have been commonly used both for core materials and for primer materials. Hence, the explosive assemblies just described have actually contained in themselves adequate primers. However, in their buried condition, the location of the cores in the assemblies cannot be determined by inspection, and they have been inaccessible for inserting blasting caps.

The present invention provides an assembly in which a core explosive may be exposed at the outside of the cartridge and, hence, is accessible for use as a primer in addition to serving its core function.

According to the invention, the gathered end of an explosive assembly such as that described above surrounds a core receptacle so that the end of the receptacle is exposed to the outside of the cartridge. The receptacle may contain the core

explosive, or the core explosive may be inserted into it later.

The explosive assembly of the present invention is conveniently manufactured by first loosely gathering the shell material around a mandrel having a diameter approximately that of the core to be employed; then inserting the core receptacle in place of the mandrel and tying the gathered portion tightly about the core receptacle. The base charge explosive may then be loaded into the shell from the opposite end after which that end may be closed in any suitable manner.

The invention will be further described in connection with the drawings in which:

Figure 1 is a side elevation partly in section of an assembly of the invention;

Figure 2 is a fragmentary side elevation partly in section in another modification of the invention;

Figure 3 is a side elevation partly in section of a shell ready to be gathered about a mandrel;

Figure 4 is a fragmentary side elevation of a shell gathered about a mandrel; and

Figure 5 is a fragmentary side elevation of a shell gathered about a core receptacle held on a mandrel.

Referring to Figure 1 of the drawings, 11 is a shell of flexible material gathered together at the top by wire tie 13 so as to surround and hold core cartridge 15. Core cartridge 15 contains core or primer explosive 17, and shell 11 contains base charge explosive 19. Tie 13 is simply a wire the ends of which are twisted together and provided with loop 21. Loop 21 is a convenient handle for the assembly and also for twisting to tighten the assembly.

Figure 2 shows an assembly somewhat similar to that shown in Figure 1. Parts shown in Figure 2 which correspond to parts shown in Figure 1 are designated by similar primed numbers. In this modification receptacle 15' is empty and open at the top, so that a core explosive may be inserted at a later time, for example, when the explosive is to be used. This embodiment of the invention has the advantage that the core explosive may be varied to suit the particular use to which the explosive is to be put.

Cap 16 is placed over the top of the assembly shown in Figure 2 to protect the open top of receptacle 15' and also to aid in sealing the assembly. A cap may be employed on the modification shown in Figure 1 as well as on that shown in Figure 2.

Figures 3 and 4 show steps in the manufacture of the assembly of Figure 1. In Figure 3,

3

shell 11 is shown in the form of a cylindrical tube. Shell 11 rests on base 23 which carries mandrel 25. Shell 11 is gathered about mandrel 25, as shown in Figure 4, and wire tie 13 is twisted around the gathered portion, shell 11 is then removed from mandrel 25, and core cartridge 15 is inserted in place of it. Wire tie 13 is then twisted by means of loop 21 to tighten shell 11 about core 15. Base charge explosive 19 is then loaded into the open end of shell 11, 10 and that end is then crimped, capped, or otherwise closed.

Figure 5 shows a step in the manufacture of the assembly of Figure 2 corresponding to the step shown in Figure 4 for the assembly of Figure 1. Core receptacle 15' is placed over mandrel 25, and shell 11' is gathered tightly about receptacle 15' by wire tie 21'. After the assembly is pulled from mandrel 25, capped and filled with explosive, the assembly shown in Figure 2 results.

It is obvious that many different shell materials may be employed for the outer shell for the assembly of the invention. The material used, however, should be sufficiently flexible to permit its being properly gathered about the core receptacle. On the other hand it should be sufficiently rugged to withstand the rough handling often received by explosive assemblies of the present type. Heavy laminated paper in the form of spiral wound tubes is one of the most satisfactory materials available. It is easily worked when freshly made and the glue is still wet. Cloth or flexible plastic materials also may be used.

While any convenient explosive material can be used for the base charge, compositions predominantly composed of ammonium nitrate are usually preferred from the point of view of cost and effectiveness of operation.

The core or primer explosive used in accordance with the invention should be sufficiently sensitive to provide certainty of initiation. Soft core materials are usually preferable because they permit ready insertion of a blasting cap. However, hard TNT type materials may be used; though in such cases it is generally desirable to provide the core with a well for the reception of a blasting cap. Ordinary nitroglycerin dynamite, and particularly gelatin dynamite because of its water resisting properties, finds especial use as core materials. When dynamite is employed, it may be used in the usual paper cartridges in which it is commonly manufactured.

When the assembly of the invention is made up without a core explosive, the core receptacle should be sufficiently rigid that it will withstand

the pressure of the base charge explosive. Ordinary mailing tube stock is highly effective for this purpose, although any other convenient material may be used.

When a cap is employed over the gathered end of the cartridge any conventional capping material or form of cap may be used. It is desirable that caps be made of frangible material so that the primer explosive may be conveniently pushed into place. Ethyl cellulose shrunk around the top is a good material, and so also is a lacquer film.

If desired, the gathered portion of the assemblies of the invention may be sealed by applying adhesive to the joint between the assembly shell and the core receptacle, or water-proofing compound may be poured into the joint from either the inside or the outside of the shell.

Other tie materials than wire, as for example, cord or strap materials, may be employed in the assemblies of the invention.

The assemblies of the invention may include conventional cores in addition to the exposed ones specifically provided for by the invention.

Other modifications of the invention will be obvious to those skilled in the art.

What is claimed is:

A method for making an explosive assembly which comprises placing a cylindrical tube over a mandrel having a diameter substantially less than that of the tube, collapsing and gathering together the periphery of an end of said tube about said mandrel, tying the collapsed and gathered portion of said tube, withdrawing said mandrel from said gathered portion, inserting a core cartridge of gelatin dynamite in place of said mandrel, tying said collapsed and gathered portion about said core, filling said shell from the opposite end with an ammonium nitrate explosive, and closing said opposite end.

WILLIAM R. FARREN.
